C. J. REDIFER.

RAIL ANCHOR.

APPLICATION FILED DEC. 28, 1916.

1,242,981.

Patented Oct. 16, 1917.

UNITED STATES PATENT OFFICE.

CHARLES J. REDIFER, OF NEW YORK, N. Y.

RAIL-ANCHOR.

1,242,981.

Specification of Letters Patent. Patented Oct. 16, 1917.

Application filed December 28, 1916. Serial No. 139,277.

To all whom it may concern:

Be it known that I, CHARLES J. REDIFER, a citizen of the United States, residing at Kings Bridge, borough of the Bronx, county 5 of Bronx, city and State of New York, have invented a new and useful Improvement in Rail-Anchors, of which the following is a specification.

My invention relates to rail anchors or 10 anti-creepers for use on railroads to prevent track rails from slipping or creeping longitudinally, and consists of a unitary structure without bolts or other fastening means of such shape as to give a reverse gripping 15 effect on the rail, and which engages with a tie so that the rail cannot creep without moving the tie with it.

The objects of my invention are to simplify the construction of the anchor by 20 constructing it of a single piece of suitable material, to so construct the device that it will effectually grip the rail in such a manner that the gripping will be increased by the 25 tendency of the rail to creep, and to so shape and construct the anchor as to give it sufficient tension to lock it to the rail when placed in position.

These and further objects will more fully appear in the following specification and accompanying drawings considered together 30 or separately.

My invention is illustrated in the accompanying drawings, in which like parts are designated by similar reference characters 35 in all of the figures, and in which—

Figure 1 is a plan view of my improved rail anchor, the rail base being shown in dotted lines;

Fig. 2 is a side elevation of the same, the 40 rail base being shown in section;

Fig. 3 is an end view of the device, the rail base being shown in side elevation;

Fig. 4 is an elevation of a rail and tie with my invention applied to prevent creeping of 45 the rail in both directions; and

Fig. 5 is a plan view of a modification.

In the drawings, 1 designates the body of the anchor which is of a general S shape. The body 1 lies under the base of the rail 2 50 and transversely of the same. The upper surface of the body 1 is provided with two raised portions 4 and 5. The raised portions are cut out to form right angle notches 6 and 7 respectively. The notches extend longitudinally of the rail base, and are engaged by the base flanges 2^a and 3 respec-

tively. The vertical face 9 of the notch 4 engages the edge of the base flange 2^a and the vertical face 9 of the notch 5 engages the opposite edge of the flange 3. The 60 notches 4 and 5 are staggered relatively to each other and face in opposite directions. The outer ends of the raised portions are vertical so as to form sharp biting corners at the terminating edges of the vertical 65 faces 9.

The body 1 is provided at one end with a projecting member or arm 10 which is curved upward and inward. The extremity of the arm 10 extends above the base flange 70 2^a and has a sharp edge 11 engaging the upper corner of such flange. The opposite end of body 1 is curved upward and inward to form a member or arm 12 which extends over the base flange 3 and is provided with 75 a sharp edge 13 which engages the upper corner of the flange 3. The vertical distance between sharp edge 11 on arm 10 and notch 6 is less than the thickness of the extremity of flange 2^a. The vertical distance 80 between sharp edge 13 on the opposite arm 12 and notch 7 is less than the thickness of the extremity of flange 3. When driven on the rail the body 1 is cramped in an upward spring twist position under the base 85 of the rail 2^a and 3 which forces the sharp edges 11 and 13 in a gripping bite against the edges of base 2^a and 3.

The notches 6 and 7 face in opposite directions so that one will tend to bite into the 90 flange when the rail moves in one direction, and the other will engage its flange when the rail tends to move in the opposite direction so as to prevent the anchor from loosening on the rail or backing off from its gripping position when the rail contacts from 95 its longitudinal creeping position freeing the projecting lug or abutment 14 from the tie 15 or by vibration of trains or otherwise. The arms 10 and 12 are curved in the reverse 100 directions giving the anchor a reverse grip to prevent the rail from creeping longitudinally, when the strain of the creeping rail forces the lug 14 against the tie 15. The notches 6 and 7 lock the anchor in the 105 opposite direction which produces four locking grips; 6 and 7 prevent the anchor from backing off or becoming loose and the sharp edges 11 and 13 lock the anchor against the creeping effect of the rail. The arms 10 and 110 12 are curved in reversed directions and give to the device its S shape.

The body 1 is provided with a downwardly projecting lug or abutment 14. This lug is situated to one side of the center of the body 1, and to one side of the center line of the rail 2, and engages with the side of the tie 15. The engaging face of lug 14 is slightly rounded horizontally to allow the lug to slide against tie 15 giving proper bearing surface when arm 12 is driven to place when the anchor is applied.

The body 1, arms 10 and 12 and lug 14 are integral, and the device is preferably formed of a cast metal such as steel which will prevent arms 10 and 12 from springing, and will force body 1 in a twisting or rolling position. While I have stated that the device may be formed of a cast metal, I wish it understood that I do not so restrict or limit myself, as the device may be made of wrought steel or other material.

The anchor shown in Fig. 5, is applied to the rail and released in connection with the form of device shown in the same manner as described in Figs. 1, 2 and 3. The same reverse grip and tie projecting abutment which gives the same leverage effect, and locked to the rail by offsets or notches is practically produced in the same manner as hereinafter described in Figs. 1, 2, and 3.

This anchor is made of uniform thickness wrought iron or steel and forged to shape.

In the modification the rail rests on the part 1 which extends from the dotted line extending from 6 to 11 to the dotted line 35 parallel thereto at 7. The part 14 shown in dotted lines corresponds to the lug 14 in the other figures. The part extending from the curved end above 6 to the point 11 lies above the base of the rail as does the part to the left of 7. The corners of the rail base are clamped at the points marked 6, 7 and 11 as in the preceding figures.

The operation of my invention is as follows:

The device is applied to the rail by hooking the arm 10 over the top of the base flange 2^a. The arm 12 is then swung toward the opposite side of the rail, and arm 12 sprung on top of the base flange 3. Arm 12 is driven toward the tie until notches 6 and 7 engage the flanges 2^a and 3. The anchor now being driven to proper position, the reverse curve shape arms 10 and 12 force body 1 in a rolling or twisting position which holds the anchor under tension. The anchor will now be firmly held to the rail, and lug 14 against tie 15 will hold the rail against movement. The more the rail has a tendency to move, the more pressure lug 14 has against tie 15, and the harder the sharp corners 11 and 13 on arms 10 and 12 will engage base 2^a and 3 as shown in Fig. 3. The lug 14 being to one side of the center line of the rail, it acts as a lever or fulcrum 65 and the leverage causes the sharp edges 11

and 13 to grip flanges 2^a and 3 respectively. Lug 14 being in engagement with the tie, the rail cannot move forward without moving the tie. Any movement of the rail has a tendency to shorten the distance between the sharp edges 11 and 13 as shown in Fig. 1, which movement will cause arms 10 and 12 to engage base 2^a and 3 in a firmer grip, which is produced by the under curve shape of arms 10 and 12 forming a tension in body 1.

If the anchor should be applied to the rail at any point where there is a deficiency in the width of the base of the rail notch 8 is provided to engage the base 3 of the rail in 80 the same manner as does the notch 5.

When it is desired to remove the anchor, the point of a crow bar can be placed between the anchor and the base of the rail near notch 5, and the anchor forced down 85 freeing notch 5 from rail base 3, and the anchor can then easily be removed.

On single track roads, in stations, on sidings and in other situations where travel is in both directions on one track, it is desirable 90 to prevent movement of the rails in both directions. To this end an anchor may be placed on the rail at each side of a tie as shown in Fig. 4.

In accordance with the provisions of the 95 patent statute, I have described the principle of my invention together with the apparatus which I now consider to represent the best embodiment thereof, but I desire to have it understood that the apparatus shown 100 is merely illustrative, and that the invention can be carried out in other ways.

Various changes in the specific form shown and described may be made within the scope of the claims without departing from 105 the spirit of my invention.

Having now described my invention, what I claim and desire to secure by Letters Patent is:

1. A device of the character described, 110 having a body, said body having an integral arm at each end thereof, said arms overhanging the upper sides of a rail base, said arms having biting portions, and means for moving the body to engage the biting portions with the rail base to prevent further relative movement of the body and rail.

2. A device of the character described, having a body, said body having an integral arm at each end thereof, said arms overhanging the upper sides of a rail base, said arms having biting portions, and means for moving the body horizontally to engage the biting portions with the rail to prevent further relative movement of the body and rail.

3. A device of the character described, having a body, said body having biting portions, said body having integral arms overhanging the sides of a rail base, opposite 130

the body, and means for moving the body to clamp the rail between the body and arms and engaging the biting portions with the rail.

5 4. A device of the character described, having an S-shaped body, with integral arms, said arms being on a different plane from the body, a tie, a rail with its base flange between the body and arms, and
10 means whereby the body may be rocked by

engagement with the tie to engage the body and arms with the bottom and top of the flange respectively.

This specification signed and witnessed this 14th day of December, 1916.

CHARLES J. REDIFER.
